US0D1029746S

(12) **United States Design Patent** (10) **Patent No.:** **US D1,029,746 S**
(45) **Date of Patent:** **** Jun. 4, 2024**

(54) **BATTERY**

(71) Applicant: **GoPro, Inc.**, San Mateo, CA (US)

(72) Inventors: **John George Muhlenkamp, IV**,
Brisbane, CA (US); **Huy Phuong Nguyen**, San Mateo, CA (US)

(73) Assignee: **GoPro, Inc.**, San Mateo, CA (US)

(**) Term: **15 Years**

(21) Appl. No.: **29/744,861**

(22) Filed: **Jul. 31, 2020**

(51) LOC (14) Cl. **13-02**

(52) U.S. Cl. USPC **D13/103**

(58) **Field of Classification Search**

USPC D13/103, 104, 107, 108, 110, 118, 119,
D13/120, 137.1, 137.2

CPC H02J 7/00047; H02J 15/00; H02J 50/05
See application file for complete search history.

(57) **CLAIM**

The ornamental design for a battery, as shown and described.

DESCRIPTION

FIG. 1 is a top, front, right side perspective view of a battery, showing our new design;

FIG. 2 is a bottom, rear, left side perspective view thereof;

FIG. 3 is a right view thereof;

FIG. 4 is a left view thereof;

FIG. 5 is a front view thereof;

FIG. 6 is a rear view thereof;

FIG. 7 is a top view thereof; and,

FIG. 8 is a bottom view thereof.

The equal-length broken lines depict portions of the battery that form no part of the claimed design.

1 Claim, 6 Drawing Sheets
